ATTACHMENT FOR SEWING MACHINES

John D. Karle, Roselle Park, N. J., assignor to
The Singer Manufacturing Company, Elizabeth, N. J., a corporation of New Jersey

Application August 1, 1933, Serial No. 683,112

12 Claims. (Cl. 112—160)

This invention relates to improvements in sewing machines and more particularly to attachments for shifting or vibrating the work laterally of the line of seam formation to produce zigzag stitches.

In the drawings:

Figure 1 is a front elevation, showing a portion of a sewing machine with my improved attachment fixed thereto.

10 Figure 2 is a view similar to Figure 1 showing the position of the parts at the beginning of the left to right shifting movement of the presser-foot.

Figure 3 is a rear elevation.

15 Figure 4 is a disassembled perspective view of the actuating mechanism.

My improved attachment is shown applied to a well known "Singer" family type sewing machine having the usual spring-pressed presser-bar 1, reciprocatory needle-bar 2, needle-clamp 3, and needle 4.

20 In its preferred embodiment the attachment comprises a channel block 5 adapted to be secured by the fastening screw 6 to the angular lower portion of the presser-bar 1. Carried by the block 5 is a plate, designated generally as 7, having an upstanding inclined arm 8 and a cross-arm 9 formed with elongated apertures 10, and outwardly projecting lips 11 which form a guiding channel. Slidably held in the guiding channel by the screws 12 is a bar 13 having a depending portion 14 to which is secured by means of the screw 15 a presser-foot 16 formed with an elongated needle-aperture 16'. Fulcrumed upon the upstanding arm 8 of the plate 7 by the stud-pin 17 is a swinging member 18 having its lower end 19 extending down between an eccentric stop 20, adjustably secured to the slide-bar 13 by the screw 21, and the end of the knurled headed adjustable stop-screw 22 fitted into a threaded aperture in the lug 23 fixed upon the end of the slide-bar. The swinging member 18 has an opening 24 (Fig. 4) with inwardly extending projections 25 and 25' adapted to embrace and engage a cam element 26 having a plurality of circumferentially spaced projections 27. Fixed to the cam-element 26 is a ratchet-wheel 28, and the cam-element and ratchet-wheel are rotatably mounted on the upstanding arm 8 of the plate 7 by means of a bearing-pin 29.

25 Pivoted secured to the arm 8 by the pivot-pin 30 is a lever 31 formed with a forwardly extending arm 32 and a rearwardly extending arm 33. The lever 31 is constantly urged downwardly by a coiled spring 34 (Fig. 4), one of the ends of the

spring acting against the arm 33 of the lever and the other end against the arm 8 of the plate. A pawl 35 is pivotally secured to the lever 31 by the pivot-pin 36 and is spring-pressed in a clockwise direction by a spring 36' which reacts between the lever 31 and the pawl 35.

Secured to the back of the arm 8 of the plate 7 by the pivot-screw 37 is a finger-lever 38 formed with a cam surface 39 and a stop 40. As viewed in Figure 3 when the finger-lever 38 is moved from the full line to the dotted line position the cam-surface 39 engages the rearwardly extending arm 33 of the lever 31 and forces it upwardly. In this position the forwardly extending arm 32 of the pawl carrying lever 31 is raised to a position 15 above the range of the needle-bar clamp 3 so that the attachment may be rendered inactive at the will of the operator and without stopping the sewing machine.

Operation

20

Assuming the needle-bar and needle to be in the position indicated in Figure 1, the needle-bar moves upward in the usual manner, and during its upward movement the needle-clamp 3 25 engages the forwardly extending arm 32 of the lever 31 and swings the lever in a clockwise direction about its pivot 30. The upward movement of the lever causes the pawl 35 to advance the ratchet-wheel one step or about one eighth of a revolution, it being understood that the distance the pawl travels on each upstroke of the needle-bar is slightly greater than the distance between the teeth on the ratchet wheel. The cam-element 26 being fixed to the ratchet-wheel 28 is 30 also moved one-eighth of a revolution. The rotation of the cam-element 26 causes one of the circumferentially spaced projections 27 to contact the inwardly extending projection 25 and force the swinging member 18 to swing clockwise 35 about its pivot 17; this swinging movement causing the lower end 19 of the member 18 to abut the adjustable eccentric stop 20 and shift the slide-bar 13 and the presser-foot 16 to the left, laterally of the line of feed. The shifting of the 40 presser-foot 16 occurs while the usual four-motion feed-dog 42 is below the throat-plate 43 and is completed just prior to the point in the cycle when the feed-dog 42 contacts the work. After the feed-dog 42 has fed the work forward the 45 needle descends, forming the stitch, and on the upstroke of the needle the needle-clamp 3 again engages the arm 32 of the lever 31 and swings the arm upward which causes the pawl 35 to again advance the ratchet-wheel one step. This causes 50 55

one of the circumferentially spaced projections 21 to contact the inwardly extending projection 25' and cam the swinging lever 18 counterclockwise about its pivot 17; this swinging movement causing the lower end 19 of the swinging lever 18 to act against the end 22' of the knurled headed screw 22 and shift the slide-bar 13 and presser-foot 16 to the right, the parts again assuming the positions, as indicated in Figure 1. From the foregoing it will be observed that in the rotation of the cam-element 26, its peripheral projections successively engage those of the swinging lever 18 to vibrate the same and thus reciprocate the slide-bar and presser-foot.

15 When it is desired to render the attachment inactive or ineffective to vibrate the presser-foot the finger-lever 38 is swung about its pivot. If the lever 31 is in the position shown in Figure 3 the upper portion of the cam surface 39 of the lever 38 moves under the rearwardly extending arm 33 and holds the lever 31 in this position, and when the lever 31 is down the cam-surface 39 engages the arm 33 and forces the lever upwardly. It will be observed that the finger-lever 38 is pivoted to the arm 8 of the plate 7; thus remaining stationary when the machine and attachment are in operation. This construction permits the operator to shift the lever at will and during the operation of the machine.

30 If the machine is being used to sew a straight seam it is obvious that the vibrating mechanism may be rendered operative to vibrate the presser-foot to produce a zigzag seam without stopping the machine and at the will of the operator. This is accomplished by simply shifting the lever 38 from the dotted line to the full line position as shown in Figure 3. This feature makes it possible to render at any time the vibrating mechanism for the work-reciprocating member or presser-foot either effective or ineffective to shift the presser-foot, thereby greatly enlarging the field of usefulness.

45 From the foregoing description considered in connection with the accompanying drawings, the construction, manner of operation and several advantages of my improved attachment will be clearly and fully understood. It is apparent that such a device has a wide variety of uses, and it will be understood that the form, construction and arrangement of the several elements employed may be varied. Therefore, the privilege is reserved of resorting to all such legitimate changes therein as may be fairly embodied within the spirit and scope of the appended claims.

50 Having thus set forth the nature of the invention, what I claim herein is:—

60 1. A sewing machine having, in combination, stitch-forming mechanism including a reciprocatory needle-bar, a needle carried thereby, a presser-bar, a frame fixed to said presser-bar, a presser-foot, means actuated by said needle-bar for imparting a vibratory motion to said presser-foot in a right line relative to said frame, and means for rendering said last named means inactive to vibrate the presser-foot at the will of the operator and without stopping the stitch-forming mechanism.

70 2. In a sewing machine, stitch-forming mechanism including a reciprocatory needle-bar, a needle carried thereby, feeding mechanism for advancing the work past the needle, a presser-foot, mechanism including a pawl for vibrating said presser-foot, means actuated by the needle-bar for operating said pawl, and means for moving said last named means out of the path of

movement of the needle-bar whereby said mechanism may be rendered ineffective.

3. In a sewing machine, a presser-bar, stitch-forming mechanism including a reciprocatory needle-bar carrying a needle, work-feeding mechanism, a presser-foot, mechanism actuated by said needle-bar for vibrating said presser-foot, said mechanism including a lever adapted to be actuated by the needle-bar, a pawl carried by said lever, and means for moving said lever to a position out of range of the needle-bar.

4. A zigzag-stitching attachment for sewing machines having, in combination, a plate adapted to be secured to the presser-bar having an upstanding arm and a cross-arm formed with a channel, a slide-bar carrying a presser-foot fitted in said channel, a swinging member having its lower end in operative engagement with said slide-bar and fulcrumed on the upstanding arm of said plate, a cam for actuating said member, and means for actuating said cam, said last named means including a spring-biased lever pivoted to the upstanding arm of said plate, a pawl pivoted to said lever, and a ratchet-wheel fixed to said cam.

5. A zigzag-stitching attachment having in combination, a plate, a slide-bar mounted on said plate, a member pivoted to said plate and in operative engagement with said slide-bar, a cam for actuating said member, a ratchet-wheel fixed to said cam, a lever also pivoted to said plate and formed with a needle-clamp engaging arm, a pawl pivoted to said lever in a position to actuate said cam, and means carried by said plate for moving and holding said lever in one extreme position of its range of operative movement.

6. A sewing machine having stitch-forming mechanism including a reciprocatory needle-bar, a pressure-bar, a frame fixed to said presser-bar, a work-vibrating member, mechanism actuated by the needle-bar and adapted to vibrate said member in a right line relative to said frame, and means for rendering said vibrating means operable at will during the operation of the stitch-forming mechanism.

7. In combination with a sewing machine having a needle-bar and a presser-bar, a plate secured to said presser-bar, a slide-bar carrying a presser-foot mounted on said plate, a swingable member pivoted to said plate and in operative engagement with said slide bar, a cam for actuating said member, a ratchet-wheel fixed to said cam, a spring-biased lever also pivoted to said plate, said lever being formed with an arm extending into the path of movement of said needle-bar, and a pawl carried by said lever for actuating said ratchet-wheel.

8. A zigzag-stitching attachment comprising a spring-biased operating lever adapted to be operated by the reciprocatory needle-bar of a sewing machine, a work-engaging member, mechanism operated by said lever for vibrating said work-engaging member, and means for moving said lever out of range of the needle-bar, whereby the vibrating mechanism may be rendered ineffective to vibrate the work-engaging member.

9. A zigzag-stitching attachment for sewing machines having a frame adapted to be secured to the presser-bar of a sewing machine, a presser-foot, and mechanism for vibrating said presser-foot relative to said frame, said mechanism including a ratchet-wheel, a cam actuated thereby and having a plurality of circumferentially spaced projections, a swinging lever having an

opening which receives said cam for actuation thereby, a lever pivoted to said frame and adapted to be actuated by the needle-bar of a sewing machine, and a pawl sustained by and movable with said lever for imparting a step-by-step movement to said ratchet-wheel.

5 10. A zigzag-stitching attachment for sewing machines having a frame adapted to be secured to the presser-bar of a sewing machine, a presser-foot, mechanism for vibrating said presser-foot relative to said frame, said mechanism including a ratchet-wheel, a cam actuated thereby and having a plurality of circumferentially spaced projections, a swinging lever having an opening 15 which receives said cam for actuation thereby, a lever pivoted to said frame and adapted to be actuated by the needle-bar of a sewing machine, a pawl sustained by and movable with said lever for imparting a step-by-step movement to said 20 ratchet-wheel, and means for rendering said vibrating means ineffective to shift the presser-foot.

11. A sewing machine having stitch-forming mechanism including a reciprocating needle, a

presser-bar, and straightaway work-feeding mechanism and a zigzag-stitching attachment comprising a frame, a presser-foot, mechanism including a pawl and ratchet actuated by the needle-bar for vibrating said presser-foot relative to said frame, and means located between said needle-bar and presser-foot for rendering said mechanism ineffective to vibrate the presser-foot at the will of the operator and without stopping the stitch-forming mechanism.

5 10 15 12. A sewing machine having stitch-forming mechanism including a reciprocating needle, a presser-bar, and straightaway work-feeding mechanism and a zigzag-stitching attachment comprising a frame, a presser-foot, mechanism including a pawl and ratchet actuated by the needle-bar for vibrating said presser-foot relative to said frame, and means located between said needle-bar and presser-foot for rendering said mechanism effective to vibrate the presser-foot at the will of the operator and without stopping the stitch-forming mechanism.

20 JOHN D. KARLE.
